UNITED STATES PATENT OFFICE.

AMANDA C. ERICSON, OF VICTORIA, ILLINOIS.

DESIGN FOR A CAKE-TURNER OR SIMILAR ARTICLE.

SPECIFICATION forming part of Design No. 32,918, dated July 10, 1900.

Application filed January 23, 1900. Serial No. 2,544. Term of patent 14 years.

To all whom it may concern:

Be it known that I, AMANDA C. ERICSON, a citizen of the United States, residing at Victoria, in the county of Knox and State of Illinois, have invented and produced a new, useful, and original Design for a Cake-Turner or Similar Article; and I do hereby declare the following, when taken in connection with the accompanying drawings and letters of reference marked thereon, to be a full, clear, and exact description of the same, and which drawings constitute a part of this specification.

The invention relates to a design for a cake-turner or similar article.

15 In the drawings, Figure 1 is a perspective view of a cake-turner or similar article embodying my design. Fig. 2 is a side elevation of my design.

Similar letters of reference indicate similar 20 parts in both figures of the drawings.

As shown, my invention comprises a long slender shank D, provided at one end with an enlarged or widened part or blade (indicated at F) and at the other with a straight cylindrical handle proper or hand part, (indicated

at E.) At the juncture of the shank and handle is a relatively-large laterally-extending bell-shaped or dished guard or shield A, on the shank side of which is a shoulder or collar C, and on the handle side of which is the shoulder or collar B, the said shoulders or collars constituting enlargements of the shank and handle, respectively.

The essential features of the design are the long slender shank, having at one end an enlarged or widened part or blade and at the other a handle with the large laterally-extending shield at the juncture of the shank and handle.

What I claim is—

40 The design for a cake-turner or similar article, substantially as herein shown and described.

In testimony whereof I have hereunto signed my name in the presence of two sub- 45 scribing witnesses.

AMANDA C. ERICSON.
